UNITED STATES PATENT OFFICE.

ALBERT W. PEARSALL, OF LOWELL, MASSACHUSETTS, ASSIGNOR TO LAMSON COMPANY, OF NEWARK, NEW JERSEY, A CORPORATION OF NEW JERSEY.

PNEUMATIC-DESPATCH-TUBE APPARATUS.

1,102,225.

Specification of Letters Patent. Patented June 30, 1914.

Application filed January 28, 1907. Serial No. 354,411.

To all whom it may concern:

Be it known that I, ALBERT W. PEARSALL, of Lowell, in the county of Middlesex and State of Massachusetts, have invented certain new and useful Improvements in Pneumatic-Despatch-Tube Apparatus, of which the following is a specification.

My invention relates to improvements in pneumatic despatch tube apparatus and particularly to automatic separating and selective despatching terminals thereof.

The main object of my invention is to receive a carrier selectively arranged and eject or tip it out of the mouthpiece or receiver, also permitting the reception of an ordinary or non-selective carrier, allowing the same to pass through without operating the selective device.

Another object of my invention is to accomplish the selection of carriers unaffected by pneumatic force, as heretofore said pneumatic force, being variable, has been unreliable. Means are also supplied whereby any number of carriers following closely upon one another are separated and spaced allowing the selection of the carriers individually unaffected by those following.

In the accompanying drawings which illustrate a construction embodying my invention, Figure 1 is a vertical section of the device on the line X X Fig. 2 looking in the direction indicated by the arrow; Fig. 2 is a rear elevation showing the device used in conjunction with an ordinary receiving terminal and showing the selective mechanism in section on line Y Y Fig. 1 looking in the direction indicated by the arrow. Fig. 3 is a perspective view of the separating and selecting device somewhat differently mounted. Fig. 4 is a perspective view of a selective carrier. Fig. 5 is a perspective view of an ordinary or non-selective carrier. Fig. 6 is a sectional view of the lower portion of a selective carrier showing the construction of the elastic selective projecting plug.

Like letters of reference refer to like parts throughout the several views.

The receiving terminal S is connected to a regular circuit of tube, the tube Q forming a part of the circuit between the said terminal and the receiving box T which is connected to another receiving terminal, which in turn, is connected to the source of air supply; thus the ordinary carrier A having passed

the usual flexible terminal valve or flap S' and been received in despaching terminal T, said carrier A being adapted not to operate the selective mechanism located in the throat between the terminal S and the terminal T, will be delivered at the terminal connected to the source of air supply.

In Fig. 1, the non-selective carrier A is shown in contact with the levers B and C and said carrier having a flat buffer, both levers are engaged thereby and move simultaneously on the pin or pivot D, thus preventing the pawl C' on the lever C from engaging the curved trip E, which trip is riveted to the arm F, thereby preventing an immediate thrust or kick being imparted through the arm F and separating lever or pusher G, consequently, the carrier A will pass down to a position below the separating lever G before any motion is imparted to said lever G. Motion will, however, be imparted to the lever G through the medium of the spring H, which is mounted on a projection F' attached to the arm F and over which projection the lever B is free to move, and which lever B pressing on the spring H imparts a thrust to the arm F and lever G which will catch the selective carrier Z preventing it from following immediately behind the carrier A. In the meantime, said carrier A holds the levers B and C depressed until it has passed beyond them, when the spring B' fixed at one end to the casing and at the other end to lever B, causes the levers B and C to resume their normal position, the weight C' holding the lever C in proper position. The screw F' threaded in the casing is adapted to be adjusted to engage the buffer F' on arm F and limit the return movement of said arm. The selective carrier Z being released after the passage of the carrier A, will then act on the lever C which is pivoted to the lever B at J. The pawl C' on the lever C will then engage the catch E imparting a thrust through the lever F to the separating lever G ejecting the carrier Z upper end foremost out of the mouthpiece K. The ordinary carrier A having passed beyond the levers C and B strikes on the spring L which imparts a thrust through the pin M to the lever N actuating the jointed lever O which folds up as shown in dotted lines Fig. 1 permitting the valve P to open inwardly and introducing the carrier A into the air circuit which is maintained through

the tube Q. This admission valve is returned to its original position and locked through the medium of the spring R acting on the rear end of the jointed lever O.

5 Fig. 6 shows a section of the selective device which is attached to both ends of the carrier Z and consists of a felt buffer Z' of the ordinary type which is secured to the carrier shell by the cup Z² which holds the buffer Z' to the shell by means of the bolts Z³. Telescoping within the cup Z² is an inverted cup Z⁴ in which is inserted a rubber packing Z⁵ projecting below the lower edge of the cup Z⁴ and against the bottom of the cup Z². The cup Z⁴ is prevented from separating from the cup Z² by the screw Z⁶ which is threaded into said cup Z². This selective projection is selectively operative only in that it hits the point of the lever C in advance of the impact of the buffer Z' on the lever B. The distance from the inner side of the tube to the end of the lever B being slightly less than the distance from the edge of the buffer Z' to the cup Z⁴ insures the depression of the lever C and the engagement of the pawl C' thereon with the catch E.

10 In Fig. 3 there is shown a view of the separating and selective device somewhat differently mounted in which corresponding parts are designated by small letters.

15 In general it will be noted that I have provided a novel means for effecting the separation of selective carriers from other or non-selective carriers, one of the most important elements of which means is the combined pusher and stop G which not only kicks the selective carrier out of the mechanism and farther out of the path of succeeding carriers but further serves to stop or arrest a succeeding carrier substantially regardless of the proximity thereof to the carrier being ejected.

20 I am aware, of course, that many changes and modifications may be made herein without departing from the spirit of my invention, and I hence desire to be limited only by the scope of the appended claims.

25 Having thus described the nature of my invention and set forth a construction embodying the same, what I claim as new and desire to secure by Letters Patent of the United States is:

30 1. In a pneumatic despatch tube apparatus, a transmission tube, a throat arranged to receive carriers emerging from said tube and to direct non-selective carriers while in rapid movement along a determined path, positive selective means for ejecting selective carriers out of said path, and a valve for normally closing communication between said tube and throat, said selective means being substantially independent of said valve.

35 2. In a despatch tube apparatus, a pneu-

matic transmission tube, a throat arranged to receive carriers emerging from said tube and to direct non-selective carriers while in rapid movement along a determined path, positive selective means for ejecting selective 70 carriers out of said path, a valve relatively remote from and substantially independent of said selective means for normally closing communication between said tube and throat, and means for leading the air current in said tube around said valve.

3. In a despatch tube apparatus, a transmission tube, selective and non-selective carriers adapted to be propelled through said tube, a throat arranged to receive carriers 80 emerging from said tube and having a side discharge opening, and means, arranged in said throat, actuated by the impact of a selective carrier and acting on said carrier at a point in the rear of its middle portion 85 to eject said carrier from the throat through said opening.

4. In a despatch tube apparatus, a pneumatic transmission tube, means, including a guiding throat, for removing carriers from 90 the influence of an air current traversing said tube, and positively acting automatic means for separating different classes of carriers according to their respective classes, after said carriers are substantially free 95 from the influence of said air current, said means including provisions for separating carriers regardless of the sequential disposition and proximity of said carriers with respect to each other.

100 5. In a despatch tube apparatus, a pneumatic transmission tube, means, comprising a valve and a by-pass, for removing carriers from the influence of an air current traversing said tube, and positively acting 105 automatic means substantially independent of said valve for separating different classes of carriers, moving with substantially the speed of transmission, according to their respective classes, after said carriers are 110 substantially free from the influence of said air current.

6. In a pneumatic despatch tube apparatus, a transmission tube, a selective mechanism in communication with said tube and adapted to receive carriers in transit through said tube, said mechanism comprising means independent of and out of contact with the air current in said tube for removing selective carriers from the path of travel 115 of non-selective carriers through said mechanism, said means including a carrier actuated pusher which normally by and during its own movement displaces selective carriers.

120 7. In a pneumatic despatch tube apparatus, a transmission tube provided with a selective mechanism adapted to receive carriers in transit, said mechanism comprising means independent of and out of con- 130

tact with the air current in said tube for kicking selective carriers from the path of succeeding carriers and arresting a succeeding carrier.

5. 8. In a pneumatic despatch tube apparatus, a transmission tube provided with a selective mechanism adapted to receive carriers in transit, said mechanism comprising means independent of and out of contact with the air current in said tube for positively propelling carriers from the path of succeeding carriers and arresting a succeeding carrier while the preceding selective carrier is being propelled from said path.
15. 9. In a despatch tube apparatus, a transmission tube and means for selectively assorting carriers delivered therethrough, said means including a device for forcibly kicking selected carriers out of the path of succeeding carriers and a carrier actuated part for operating said kicking device, and a valve through which said carriers pass to said device.
25. 10. In a despatch tube apparatus, a transmission tube provided with a selective mechanism adapted to receive carriers in transit, said mechanism comprising means for arresting the advance of selective carriers and means for ejecting said carriers rear end foremost out of the path of non-selective carriers, and a valve through which said carriers pass to said mechanism.
35. 11. In a despatch tube apparatus, a transmission tube provided with a selective mechanism adapted to receive carriers in transit, said mechanism comprising means for arresting the advance of selective carriers and a pusher which normally by and during its own movement displaces the selective carriers out of the path of non-selective carriers and out of said apparatus.
45. 12. In a despatch tube apparatus, a transmission tube provided with a selective mechanism adapted to receive carriers in transit, and a valve through which said carriers are delivered from said tube to said mechanism, said mechanism comprising means for arresting the advance of selective carriers and a pusher which normally by and during its own movement displaces the rear ends of said selective carriers out of the path of non-selective carriers prior to the displacement of the forward ends of said carriers from said path.
55. 13. In a despatch tube apparatus, a transmission tube provided with a selective mechanism adapted to receive carriers in transit, said mechanism comprising means for arresting the advance of selective carriers, a movable member and co-acting means for operatively pressing said member against selective carriers only, after the latter have engaged said arresting means, to eject said selective carriers from said apparatus.
65. 14. In a despatch tube apparatus, a trans-

mission tube provided with a selective mechanism adapted to receive carriers in transit, said mechanism comprising means for arresting the advance of selective carriers, a pusher which normally by and during its own movement displaces the selective carriers out of the path of non-selective carriers and out of said apparatus, and connections between said pusher and arresting means for actuating said pusher through the instrumentality of said selective carriers.

70. 15. In a pneumatic despatch tube apparatus, a transmission tube, a selective mechanism in communication with said tube and adapted to receive carriers in transit through said tube, said mechanism comprising means independent of and out of contact with the air current in said tube for removing selective carriers from the path of travel of non-selective carriers through said mechanism, said means including a pusher which normally by and during its own movement ejects selective carriers from said apparatus.
80. 16. In a despatch tube apparatus, a transmission tube, a valve, and mechanism for selectively assorting carriers delivered thereto past said valve by said tube, said mechanism including means for displacing a part at least of a selective carrier out of the path of a succeeding carrier, said mechanism having provisions for stopping said succeeding carrier while the selective carrier is being removed from its path and said displacing means adapted to move said part of said selective carrier substantially at right angles to said path.

90. 17. In a despatch tube apparatus, a transmission tube, a valve, and mechanism for selectively assorting carriers delivered thereto past said valve by said tube, said mechanism including means for arresting a selective carrier and displacing sidewise a rear part at least thereof out of the path of a succeeding carrier, at least as soon as a front part thereof is correspondingly displaced, said mechanism having provisions for stopping said succeeding carrier after it has passed said valve and while the selective carrier is being removed from its path.

100. 18. In a despatch tube apparatus, a transmission tube and mechanism for selectively assorting carriers delivered thereto by said tube, said mechanism including means for reversing the direction of travel of a part of each and every selective carrier delivered thereto and co-acting means for positively directing said selective carrier into a path at variance with that traveled by non-selective carriers, and substantially directly out of said apparatus.

110. 19. In a despatch tube apparatus, a transmission tube, a valve, and means for selectively assorting carriers delivered therethrough, said mechanism including a combined pusher and stop for carriers, said

pusher adapted to kick selected carriers out of the path of succeeding carriers by a movement thereof and to stop a succeeding carrier when ejecting a preceding carrier, said succeeding carrier when stopped by said pusher being out of the air current passing through said tube.

20. In a despatch tube apparatus, a transmission tube, a valve, and means below said valve for selectively assorting carriers delivered therewith, said means including a combined pusher and stop for carriers, said pusher adapted to kick selected carriers out of the path of succeeding carriers by a movement thereof and to stop a succeeding carrier when ejecting a preceding carrier, and means, engaged by a carrier to be ejected, for actuating said combined pusher and stop.

20 21. In a despatch tube apparatus, a transmission tube provided with a selective mechanism adapted to receive carriers in transit, said mechanism comprising means for arresting the advance of selective carriers and a pusher which normally by and during its own movement displaces the selective carriers out of the path of non-selective carriers, said mechanism also including auxiliary provisions in connection
25 30 with said pusher for arresting a selective carrier closely following a non-selective carrier passing through said mechanism, whereby positive separation of all selective from non-selective carriers is assured.

35 22. In a despatch tube apparatus, a transmission tube provided with a selective mechanism adapted to receive carriers in transit, said mechanism comprising a pusher which normally by and during its own movement
40 displaces the selective carriers out of the path of non-selective carriers, said mechanism also including auxiliary provisions in connection with said pusher for arresting a selective carrier closely following a non-
45 selective carrier passing through said mechanism, whereby positive separation of all selective from non-selective carriers is assured.

23. In a despatch tube apparatus, a transmission tube provided with a selective mechanism adapted to receive carriers in transit, selective and non-selective carriers, carriers of one of said classes being provided with means for spacing the head thereof from the head of a carrier of the other class when said carriers closely follow each other through said tube, said mechanism being selectively operated by said spacing means and comprising means for arresting the advance of selective carriers and a pusher which normally by and during its own movement displaces the selective carriers out of the path of non-selective carriers.

24. In a despatch tube apparatus, carriers
65 of two classes, cartiers of one of said classes

having spacing extensions upon the heads thereof, a transmission tube for said carriers provided with a selective mechanism adapted to receive carriers in transit, said mechanism being selectively operated by one of said classes of carriers and comprising a pusher which normally by and during its own movement displaces carriers of one of said classes out of the path of carriers of the other class, said mechanism having provisions for arresting a carrier closely following a preceding carrier while the latter is subject to the action of said pusher. 70 75

25. In a despatch tube apparatus, carriers of two classes, carriers of one of said classes having spacing extensions upon the heads thereof, a transmission tube for said carriers provided with a selective mechanism adapted to receive carriers in transit, said mechanism being selectively operated by one of said classes of carriers and comprising a pusher which normally by and during its own movement displaces carriers of one of said classes out of the path of carriers of the other class, said mechanism having provisions for arresting a carrier closely following a preceding carrier while the latter is subject to the action of said pusher, said mechanism also having means for controlling actuations thereof by the engagement of said spacing extensions with a part of said means. 93

26. In a despatch tube apparatus, carriers of two classes, carriers of one of said classes having spacing extensions upon the heads thereof, a transmission tube for said carriers provided with a selective mechanism adapted to receive carriers in transit, said mechanism being selectively operated by one of said classes of carriers and comprising a pusher which normally by and during its own movement displaces carriers of one of said classes out of the path of carriers of the other class, said mechanism having provisions for arresting a carrier closely following a preceding carrier while the latter is subject to the action of said pusher, said mechanism also having means for stopping a carrier in transit therewith when said carrier is subject to the action of said pusher. 100 105 110 115

27. In a despatch tube apparatus, carriers of two classes, carriers of one of said classes having spacing extensions upon the heads thereof, a transmission tube for said carriers provided with a selective mechanism adapted to receive carriers in transit, said mechanism being selectively operated by one of said classes of carriers and comprising a pusher which normally by and during its own movement displaces carriers of one of said classes out of the path of carriers of the other class, said mechanism having provisions for arresting a carrier closely following a preceding carrier while the latter 120 125 130

is subject to the action of said pusher, said mechanism having means for stopping a carrier in transit therepast when said carrier is subject to the action of said pusher, and provisions adapted to co-act with said last mentioned means for controlling the actuation of said pusher by said spacing extensions.

In testimony whereof, I have signed my name to this specification in the presence of two subscribing witnesses, this 25th day of January A. D. 1907.

ALBERT W. PEARSALL.
